LUBRICATOR AND STRAINER

Sidney G. Down, Edgewood, Pa., assignor to The Westinghouse Air Brake Company, Wilmerding, Pa., a corporation of Pennsylvania

Application February 28, 1935, Serial No. 8,641

16 Claims. (Cl. 184—55)

This invention relates to means for cleaning and supplying lubricant to air flowing through a pipe.

One object of the invention is to provide a combined lubricator and strainer adapted to remove dirt or foreign matter from the air and to supply a lubricating medium to the air which passes through the device, and adapted to be interposed in the air line leading to an air controlling device, such as the steam governor employed to control the operation of a steam driven air compressor.

A further object of the invention is to provide a device of the character described in which the air flowing through the device normally passes through a straining or cleaning element, and in which the flow of air through the straining or cleaning element may be cut off without cutting off the flow of air through the device.

Another object of the invention is to provide a device of the character described having an air straining or cleaning element through which the air normally flows and which can be removed when desired without cutting off the flow of air through the device.

A further object of the invention is to provide a lubricating and straining device adapted to be interposed in an air supply line and in which valve means is provided to control the flow of air through an air straining or cleaning element incorporated in the device or to by-pass the air around the cleaning or straining element, and having a signal which is operable when the valve means is conditioned to by-pass air around the air straining or cleaning element.

Other objects of the invention and features of novelty will be apparent from the following description taken in connection with the accompanying drawings, in which

Figure 1 is a diagrammatic view of a compressor control system incorporating the combined lubricator and strainer provided by my invention, the compressor governor and a portion of the engineer's brake valve device being shown in section;

Figure 2 is a sectional view taken substantially along the line 2—2 of Figure 1;

Figure 3 is a sectional view taken substantially along the line 3—3 of Figure 2;

Figure 4 is a sectional view taken substantially along the line 4—4 of Figure 2;

Figure 5 is a sectional view taken substantially along the line 5—5 of Figure 1; and

Figure 6 is a view similar to Figure 2 but

showing the valve means turned to a different rotative position.

Referring to the drawings, I have shown the combined lubricator and strainer provided by my invention incorporated in the control system for a steam driven air compressor. As shown in the drawings the combined strainer and lubricator provided by my invention is indicated generally by the reference character 10, and is interposed in the pipe which leads from the engineer's brake valve device 11 to the low pressure top 13 of the compressor governor which is indicated generally by the reference character 12. The brake valve device 11 has a valve chamber which communicates with the main reservoir 16 by way of a pipe 17, while a pipe 18 connects the main reservoir 16 with the high pressure top 20 of the governor 12 so that the high pressure top 20 is always subject to the pressure of the fluid in the main reservoir 16.

The brake valve device 11 has a rotary valve 22 controlled by the handle 23, the rotary valve 22 having a port 24 therein to control communication from the valve chamber and the main reservoir 16 to the pipe 14 which leads to the lubricator and strainer 10. The port 24 is arranged so as to establish communication for supplying fluid under pressure from the main reservoir to the pipe 14 in certain positions of the operating handle 23, and it is preferably arranged so as to supply fluid to the pipe 14 when the operating handle is in the release, running and holding positions, and to cut off communication between the main reservoir and the pipe 14 in other positions of the brake valve handle. When running over the road, therefore, with the brakes released, fluid under pressure is supplied to the low pressure top 13 of the governor which serves to control the air compressor.

As shown in Figure 1 the governor 12 may be of the well known type comprising a steam valve body 25, a cylinder section 26, and a cylinder head 27 in which are secured the low pressure top section 13 and the high pressure top section 20. The body 25 is provided with a partition wall 30 which separates the steam inlet chamber 32 from the outlet chamber 33 and is provided with a valve seat for a steam valve 34 which is carried by a stem 35. Loosely carried within an axial bore in the stem 35 of the steam valve 34 is a stem 40 the upper end of which is pressed into an axial bore in a piston 41 which works in a bushing 50 secured in the cylinder section 26.

The two governor heads each comprise a spring box 55 secured in the head 27. A valve seat 55

bushing 57 provided with an annular flange 58 is mounted below the spring box 55 and a flexible diaphragm 59 is mounted between the spring box and the valve seat bushing. A valve element 62 is mounted in the valve seat bushing 57 and engages a seat provided in the bushing. The valve element 62 is provided with a rectangular guide head 63, the rounded corners of which engage a cylindrical guide wall in the bushing, and when 10 the corners are in such engagement, there will be spaces between the straight sides of the head and the walls of the bushing through which fluid under pressure supplied to the passages 65 in the bushing is supplied to the chamber at one side 15 of the flexible diaphragm 59.

Mounted in a chamber in the bushing 57 is a coil spring 58 having one end in engagement with a spring plate 69 which is provided with a central depression adapted to receive the rounded 20 end of a stem 70 carried by the valve 62.

The spring box 55 has an adjustable coil spring 75 mounted therein, one end of which bears upon a plate 76 engaging the diaphragm 59. The upper end of the spring 75 engages a spring plate 25 77 which is engaged by the end of the adjusting screw 79.

The left hand governor top, which is indicated by the reference character 29, is known as the high pressure top, and the right hand governor top, which is indicated by the reference character 13, is known as the low pressure top. The spring 75 of the low pressure top is responsive to a lower pressure acting on the diaphragm 59 associated with this portion of the governor than 30 the spring 75 of the high pressure top.

In operation the chamber on the lower side of the diaphragm 59 of the high pressure top is supplied with fluid under pressure from the main reservoir 16 by way of pipes 17 and 18, and the chamber on the under side of the diaphragm 59 of the low pressure top is supplied with fluid at the pressure compressed by the compressor into the main reservoir when the brake valve handle 23 is moved to certain of its positions. 40 The fluid which is supplied to the chambers on the lower sides of the diaphragms of the governor tops urges these diaphragms upwardly, and if the pressure of the fluid supplied to either of these chambers is of sufficiently high value, the 45 diaphragm associated with this chamber will be flexed upwardly to permit one of the valve elements 62 to be unseated by the spring 68 associated therewith. When a valve element 62 is unseated fluid under pressure flows from the 50 chamber on the lower side of the diaphragm to the chamber on the upper face of the piston 41, forcing the piston downwardly and thereby moving the steam valve 34 to the closed position to 55 cut off the supply of steam to the compressor.

60 The springs 75 associated with the high and low pressure tops are adjusted so that different fluid pressures in the chambers beneath the diaphragms are required to move the diaphragms against the springs. The spring 75 associated 65 with the high pressure top 20 is adjusted so that a somewhat higher pressure is required to move the diaphragm associated with this top than is required to move the diaphragm associated with the low pressure top 13.

70 When fluid under pressure is supplied to the low pressure top 13, this top will operate to control the operation of the compressor controlled by the governor, and when the supply of fluid to the low pressure top is cut off the compressor 75 will be controlled by the high pressure top. The

supply of fluid to the low pressure top is controlled by the engineer's brake valve device so that fluid is supplied to the low pressure top when the brake valve device is in the release, running and holding positions. The brake valve 5 device is in one of these positions a large portion of the time, so that during all except a small portion of the time the air compressor will be controlled by the low pressure top.

The fluid which is supplied to the low pressure 10 top of the governor flows from the engineer's brake valve device 11 through the pipe 14, and thence through the lubricator and strainer provided by my invention which serves to clean and remove all dirt from the air which flows to 15 the governor, and to supply to the air a limited amount of lubricant which is carried by the air to the compressor governor to lubricate the parts of the governor.

The construction of the combined lubricator 20 and strainer provided by my invention is shown in detail in Figures 2 to 6 of the drawings, and, as illustrated, comprises a body 90 having a chamber 91 formed in the lower portion thereof and having a taper plug valve element 93 adapted 25 to be operated by a handle 94 fitted in the upper portion thereof. A cap nut 95 is screwed into the valve body to close the opening at the larger end of the valve, and a spring 96 is positioned between the cap nut 95 and the end of the valve 30 93 and tends to maintain said valve seated.

The body 90 also has a chamber 100 formed in the upper portion thereof and which communicates with the chamber 91 by way of a passage 101 which is closed by a cap nut 102 which 35 is screwed into the body 90. A quantity of suitable air cleaning material, such as curled hair indicated at 104, is placed in the chamber 100. The curled hair 104 is held in position by means of perforated discs 105 which are secured together by means of a rivet 106. The lower disc 105 rests upon a shoulder formed around the passage 101 leading from the lower end of the chamber 100, while a tubular bushing 108 extends between the upper disc 105 and the lower 40 45 face of the cap nut 102, and serves to maintain the curled hair in position in the chamber 100.

Means is provided to supply lubricant to the chamber 91 and this means comprises an opening 110 which communicates with the chamber 50 91, and which is closed by means of a threaded plug 111. The opening 110 communicates with the chamber 91 at a point vertically below the passage 101 leading from the chamber 100 to the chamber 91 and is arranged so that the level 55 to which the lubricant in the chamber 91 may be raised will be below the lower end of the chamber 100 in which the air strainer is positioned.

The body 90 has a chamber 115 formed there-in adjacent the valve 93 and this chamber communicates with the upper portion of the chamber 91 by way of a passage in a curved tubular member 116. A wick 118 is provided which has one end thereof positioned in the curved tubular 65 member 116 and which has its lower end submerged in the lubricant in the chamber 91.

The body 90 also has a substantially cylindrical opening 120 formed therein and in which is adapted to be secured in any suitable manner, 70 the end of the pipe 14 leading from the engineer's brake valve device. A passage 121 communicates with the opening 120 and leads to the valve 93 which has a passage or port 122 formed therein, and which, in certain positions 75

of the valve 93, is in alignment with the passage 121 and with a passage 123 leading to the chamber 100 so as to establish communication between the pipe 14 and the chamber 100.

5 The valve 93 has a passage 125 formed therein and extending generally axially thereof and has at one end of this passage a port 126, which is adapted in one position of the valve 93 to communicate with the passage 121, and has at 10 the other end of the passage 125 a port 127, which is adapted in the same position of the valve element to communicate with a passage 128 leading to the cylindrical opening 130 in which is secured in any suitable manner the pipe 131 15 leading from the strainer and lubricator to the low pressure top 13 of the governor. The valve 93 is also provided with a port 133 which communicates with the passage 125 and with a vent port 134 formed in the body 90 of the lubricating and straining device. The port 133 is arranged so as to communicate with the vent port 134 when the ports 126 and 127 are in alignment with the passages 121 and 123, respectively.

25 The valve 93 also has a port 135 formed therein and communicating, in one position of the valve 93, with the chamber 115 and with the passage 130 in which is secured the discharge pipe 131.

30 The valve 93 also has a shallow oil distributing groove 137 formed therein and extending axially from the port 135. This groove serves to distribute oil over the wall of the cavity in which the valve is located to lubricate this wall and the 35 valve.

In the operation of the combined strainer and lubricator provided by my invention air is supplied to the device by way of the pipe 14, and with the valve 93 in the position shown in Figure 40 2 of the drawings, air flows from the pipe 14 to the passage 121 and through the port or passage 122 in the valve element 93 to the passage 123, and thence to the chamber 100 and through the curled hair 108, which cleans the air and 45 removes any particles of dirt which may be present therein. From the chamber 100 the air flows through the passage 101 to the chamber 91 which contains the lubricant, and from this chamber the air flows through the tubular member 116 to the chamber 115. The wick 118 fits loosely enough in the tubular member 116 to permit air to flow freely through the member 116. The wick 118 is saturated with oil due to 50 capillary action and it carries a small amount of oil into the chamber 115, and as the air flows over the wick 118 it picks up a portion of the oil present in the wick. From the chamber 115 the air flows through the passage 135 in the valve 93 and therefrom to the passage 130, and 55 thence through the pipe 131 to the compressor governor. In the preferred embodiment the pipe 131 is relatively short, the combined strainer and lubricator being placed as near the governor as possible. The air which flows to the governor will contain a limited amount of lubricant which will be deposited upon the working parts of the governor so as to lubricate the governor.

The combined lubricator and strainer provided by this invention incorporates means by which 70 the flow of air from the supply pipe 14 to the discharge pipe 131 may be by-passed around the air strainer and the chamber containing the lubricant if desired. This is accomplished by turning the valve 93 one quarter of a turn by 75 means of the handle 94. A projection on the

housing and indicated at 140 engages a projection 141 on the handle to limit the amount of rotation of the valve 93 by the handle and these projections are arranged to prevent rotation of the valve element beyond the point at which the ports in the valve element are in alignment with the ports in the housing 90.

When the valve 93 has been rotated one quarter turn from the position shown in Figure 2 the valve will be in the position shown in Figure 6, in which it will be seen that the passage 122 is moved out of communication with the passage 121 leading from the pipe 14, and out of communication with the passage 123 leading to the chamber 100 so as to cut off the flow of fluid from the pipe 14 to the chamber 100. It will be seen also that the port 135 is moved out of communication with the chamber 115 and the pipe 131 so as to cut off communication between the chamber 91 and the discharge pipe. 20 The chamber 100 and the reservoir chamber 91, therefore, are cut off from both the supply and discharge pipes associated with the device.

When the valve element 93 is in the position shown in Figure 6, the port 126 is in communication with the passage 121 leading from the supply pipe 14, and fluid under pressure can flow from the supply pipe 14 through the passage 121, and the port 126 to the passage 125 in the valve 93, and therefrom through the port 127 to the passage 128 leading to the discharge pipe 131. At the same time the port 133, which leads from the passage 125, is moved into communication with the vent port 134 formed in the body 90 so that fluid under pressure in the passage 125 can escape through the vent port. This provides an audible signal or indication that the valve has been turned to the position in which the flow of fluid through the combined lubricator and strainer is by-passed around the lubricating 40 and straining means.

With the valve 93 in the position shown in Figure 6, the supply of fluid under pressure to the compressor governor is maintained independently of the strainer and the lubricating chamber. 45 With the valve in this position the air straining element may be removed for cleaning or replacement if desired, and this may be accomplished by removing the cap nut 102 and lifting the air straining element out of the chamber 100. Similarly, the supply of lubricant in the chamber 91 may be replenished, this being accomplished by removing the plug 111 and pouring lubricant into the chamber 90 through the passage 110 until the lubricant overflows and runs out of the 55 passage.

After the plug 111 and the cap nut 102 have been replaced the combined lubricator and strainer is restored to normal operation by turning the valve 93 back one quarter turn so that the 60 passage 122 is in alignment with the passages 121 and 123, and so that the passage 135 is in communication with the chamber 115 and the discharge pipe 131. The handle 94 is provided with a lug 142 adapted to engage the projecting portion 140 on the housing to prevent rotation of the valve beyond this point.

When the valve has been turned to the position in which communication is established between the supply pipe 14 and the chamber 100, 70 and between the chamber 91 and the exhaust or discharge pipe 131, communication between the passage 125 formed in the valve 93 and the supply pipe by way of the port 126, and the discharge pipe by way of the port 127, and the vent 75

passage 134 by way of the port 133 is cut off. From the foregoing it will be seen that the improved lubricator and strainer provided by my invention is adapted to be interposed in the air supply line leading to the governor employed in connection with a steam driven air compressor, and that the lubricator and strainer provides means to strain or clean the air which passes through it and to supply a limited quantity of lubricant to the air, which lubricant will be carried to the governor to lubricate it.

It will be seen also that the lubricator and strainer provided by my invention incorporates means by which the flow of air through the device 15 may be maintained while the flow of air through the air strainer incorporated in the device is cut off. In addition it will be seen that the lubricator and strainer provided by this invention has a vent passage through which air is permitted to escape 20 to the atmosphere when the device is conditioned to by-pass the flow of air around the air strainer incorporated in the device, thereby providing an audible signal which indicates that the air strainer has been cut out of the passage through which 25 the air flows through the device.

It will be seen also that the improved lubricating and straining device provided by this invention incorporates means by which the air strainer employed in the device may be removed 30 for cleaning or other purposes, and by which the supply of lubricant in the device may be replenished without interrupting the flow of fluid through the device.

While one embodiment of the invention has 35 been illustrated and described in detail, it should be understood that the invention is not limited to these details of construction and that numerous changes and modifications may be made without departing from the scope of the following 40 claims.

Having now described my invention, what I claim as new and desire to secure by Letters Patent, is:

1. In a device of the class described and adapted to be interposed in a fluid supply pipe, said device having a pair of passages therethrough, fluid straining means and lubricant supplying means associated with one of said passages, the other of the passages being adapted to establish communication through the fluid supply pipe independently of the fluid straining means and the lubricant supplying means, and valve means operable to direct the flow of fluid through the device through either of said passages, and to 55 cut off the flow of fluid through the other of said passages.

2. In a device of the class described and adapted to be interposed in a fluid supply pipe, said device having a pair of passages therethrough, fluid straining means and lubricant supplying means interposed in one of said passages, a vent passage associated with the other of said passages, and valve means operable to direct the flow of fluid through the device through either 60 of said passages and to cut off the flow of fluid through the other of said passages.

3. In a device of the class described and adapted to be interposed in a fluid supply pipe, a body having a chamber therein adapted to hold a 65 quantity of lubricant, the body having a supply passage therein adapted to be connected to a source of fluid under pressure and having an exhaust passage therein leading from said device, the chamber communicating with the supply and 70 exhaust passages, a fluid strainer interposed in 75

the communication between the supply passage and the chamber, and valve means controlling the flow of fluid from the supply passage to said chamber and from said chamber to the exhaust passage, and controlling a communication between said supply passage and said exhaust passage independent of said chamber. 5

4. In a device of the class described and adapted to be interposed in a fluid supply pipe, a body having a chamber therein adapted to hold a 10 quantity of lubricant, the body having a supply passage therein adapted to be connected to a source of fluid under pressure, and having an exhaust passage therein leading from said device, the chamber communicating with the supply and 15 exhaust passages, a fluid strainer interposed in the communication between the supply passage and the chamber, and a single valve element controlling communication between the supply passage and said chamber, between the chamber and the exhaust passage, and between the supply passage and the exhaust passage independent of the chamber. 20

5. In a device of the class described and adapted to be interposed in a fluid supply pipe, a 25 body having a chamber therein adapted to hold a quantity of lubricant, the body having a supply passage therein adapted to be connected to a source of fluid under pressure, an exhaust passage therein leading from said device, and having 30 a vent passage formed therein, the chamber communicating with the supply and exhaust passages, a fluid strainer interposed in the communication between the supply passage and the chamber, and valve means controlling the flow of fluid from 35 the supply passage to said chamber and from said chamber to the exhaust passage, and between the supply passage and the vent passage. 40

6. In a device of the class described and adapted to be interposed in a fluid supply pipe, a body having a chamber therein adapted to hold a quantity of lubricant, the body having a supply passage therein adapted to be connected to a source of fluid under pressure, an exhaust passage therein leading from said device, and having 45 a vent passage formed therein, the chamber communicating with the supply and exhaust passages, a fluid strainer interposed in the communication between the supply passage and the chamber, and a single valve controlling communication between the supply passage and said chamber, between the chamber and the exhaust passage, between the supply passage and the exhaust passage independent of the chamber, and 50 between the supply passage and the vent passage. 55

7. In a device of the class described and adapted to be interposed in a fluid supply pipe, a body having a chamber therein adapted to hold a quantity of lubricant, the body having a supply passage therein adapted to be connected to a source of fluid under pressure, and having an exhaust passage therein leading from said device, the chamber communicating with the supply and exhaust passages, a fluid strainer interposed in 60 the communication between the supply passage and the chamber, and a single valve element controlling communication between the supply passage and said chamber, between the chamber and the exhaust passage, and between the supply 65 passage and the exhaust passage independent of the chamber, said valve element being movable between spaced positions and being adapted in one of said positions to open communication between the supply passage and said chamber. 70 75

and between the chamber and the exhaust passage, and to close communication between the supply passage and the exhaust passage, and being adapted in the other of said positions to cut off communication between the supply passage and said chamber, and between said chamber and the exhaust passage, and to open communication between the supply and exhaust passages independently of said chamber.

8. In a device of the class described and adapted to be interposed in a fluid supply pipe, a body having a chamber therein adapted to hold a quantity of lubricant, the body having a supply passage therein adapted to be connected to a source of fluid under pressure, an exhaust passage therein leading from said device, and having a vent passage formed therein, the chamber communicating with the supply and exhaust passages, a fluid strainer interposed in the communication between the supply passage and the chamber, and valve means controlling the flow of fluid from the supply passage to said chamber and from said chamber to the exhaust passage, said valve element being movable between spaced positions and being adapted in one of said positions to open communication between the supply passage and said chamber, between the chamber and the exhaust passage, and to close direct communication between the supply passage and the exhaust passage, and to close communication between the supply passage and the vent passage, and being adapted in the other of said positions to cut off communication between the supply passage and said chamber and between said chamber and the exhaust passage, and to open communication between the supply and exhaust passages independently of said chamber and to open communication between the supply passage and the vent passage.

9. In a device of the class described and adapted to be interposed in a fluid supply pipe, a body having a chamber therein adapted to hold a quantity of lubricant, the body having a supply passage therein adapted to be connected to a source of fluid under pressure and having an exhaust passage therein leading from said device, the chamber communicating with the supply and exhaust passages, a fluid strainer interposed in the communication between the supply passage and the chamber, valve means controlling the flow of fluid from the supply passage to said chamber and from said chamber to the exhaust passage, a wall of said chamber having an opening therein through which lubricant may be added to said chamber, said opening being located vertically below the point at which the passage leading from the chamber to the exhaust passage communicates with said chamber, and a wick having one end thereof immersed in the lubricant in said chamber and having the other end thereof positioned in the passage leading from said chamber.

10. In a device of the class described, in combination, a pipe through which fluid is adapted to flow, a casing interposed in said pipe and having a chamber containing a body of lubricant and having a passage, communication for the flow of fluid through said pipe being established by way of said chamber and said passage and a wick extending into said passage and supplied with lubricant from said body of lubricant by capillary action.

11. In a device of the class described, in combination, a pipe through which fluid under pres-

sure flows, a casing interposed in said pipe, a fluid strainer, and valve means in said casing having one position in which communication is established for the flow of fluid through said pipe by way of said fluid strainer and another 5 position in which communication is established for the flow of fluid through said pipe independently of said strainer.

12. In a device of the class described, in combination, a pipe through which fluid under pressure flows, a casing interposed in said pipe, means for supplying lubricant to fluid flowing through said pipe, and valve means in said casing having one position in which communication is established for the flow of fluid through said pipe by 10 15 way of said lubricant supplying means and another position in which communication is established for the flow of fluid through said pipe independently of said lubricant supplying means.

13. In a device of the class described, in combination, a pipe through which fluid under pressure flows, a casing interposed in said pipe, a fluid strainer, means for supplying a lubricant to the fluid flowing through said pipe, and valve means in said casing having one position in 20 25 which communication is established for the flow of fluid through said pipe by way of said fluid strainer and said lubricant supplying means and another position in which communication is established for the flow of fluid through said pipe 30 independently of said strainer.

14. In combination, a steam pump governor, an engineer's brake valve device, a pipe through which fluid under pressure is supplied by said valve device to said governor, a casing interposed 35 in said pipe, means in said casing for filtering the fluid flowing through said pipe and for supplying lubricant to the fluid flowing through said pipe, and valve means for controlling communication through which fluid flows through said 40 filtering and lubricant supplying means and operable to establish communication through said pipe independently of said filtering and lubricant supplying means.

15. In a device of the class described, in combination, a pipe through which fluid under pressure flows, a casing interposed in said pipe, a fluid strainer, means for supplying lubricant to the fluid flowing through said pipe, and valve means in said casing having one position in which communication is established for the flow of fluid through said pipe by way of said fluid strainer and said lubricant supplying means, and another 50 55 position in which communication is established for the flow of fluid through said pipe independently of said fluid strainer and said lubricant supplying means.

16. In a device of the class described, in combination, a pipe through which fluid under pressure flows, a casing interposed in said pipe, a fluid strainer, means for supplying lubricant to the fluid flowing through said pipe, said casing having a vent passage formed therein, and valve means in said casing having one position in which communication is established for the flow of fluid through said pipe by way of said fluid strainer and said lubricant supplying means, and another 60 65 position in which communication is established for the flow of fluid through said pipe independently of said fluid strainer and said lubricant supplying means, and in which communication is established through said vent passage.
